UNITED STATES PATENT OFFICE.

EDWARD YOUNG MOORE, OF CLEVELAND, OHIO.

HOISTING MECHANISM.

Specification of Letters Patent. Patented Sept. 29, 1914.

1,112,153.

Application filed December 29, 1913. Serial No. 809,309.

To all whom it may concern:

Be it known that I, EDWARD Y. MOORE, a citizen of the United States, residing at Cleveland, in the county of Cuyahoga and State of Ohio, have invented a certain new and useful Improvement in Hoisting Mechanism, of which the following is a full, clear, and exact description, reference being had to the accompanying drawings.

10 The object of this invention is to provide an efficient hoisting mechanism adapted at will to raise or lower its load slowly and gradually or comparatively rapidly. To this end I have provided two adjacent sprocket wheels having, respectively, a different number of teeth or pockets, mechanism for slowly rotating one of the sprocket wheels, and means for clutching the other sprocket wheel to its neighbor or to the stationary support, whereby a hoisting chain may be fed differentially or may be anchored and given a direct pull.

My invention is hereinafter more fully described in connection with an approved embodiment thereof and the essential characteristics are summarized in the claims.

In the drawings, Figure 1 is a side elevation of my hoisting mechanism; Fig. 2 is a vertical section along the main shaft; Fig. 3 is an end view looking from the right hand end of Fig. 1; Fig. 4 is a vertical section through the driving mechanism on the line 4—4 of Fig. 2 looking toward the left; Fig. 5 is a vertical section on the line 5—5 of Fig. 2 looking toward the right; Fig. 6 is a detail illustrating the braking device.

In the drawings, 10 indicates a suitable form having standards 11 and 12 in which is journaled a shaft 13. Keyed on this shaft 40 is a sprocket wheel 15. Slidably mounted on the shaft is an adjacent sprocket wheel 16. The sprocket wheels 15 and 16 have respectively different numbers of teeth. For instance, one of them may have eighteen teeth and the other nineteen, for the particular number is immaterial. The sprocket teeth may be of any desired form, according to the chain with which they are to coöperate. As shown, they are of the usual pocket construction and are adapted to receive an ordinary chain.

The two sprocket wheels 15 and 16 are provided on their adjacent sides with clutch teeth 21 and 22, which are designed to coact 55 to lock the two sprockets together, when desired. When so locked (as shown in Figs.

1 and 2) the two sprocket wheels are rotated together and act after the manner of the well-known differential pulley.

Rigid with the sprocket wheel 16 is a second set of clutch teeth 23, these teeth being shown as carried on a disk 24 surrounding the hub of the sprocket wheel 16 and rigidly bolted to it through spacing sleeves 26. The teeth 23 are adapted to coöperate with teeth 27 projecting from the face of the disk 28 which is formed on or secured to the frame standard 11.

From the construction described, it follows that, if the sprocket wheel 16 is shifted toward the left from its position in Figs. 1 and 2, it becomes locked against rotation. This anchors the chain which surrounds that pulley, so that a rotation of the pulley 15 makes a direct pull on the chain, thus driving it at a much more rapid speed than the differential drive.

The chain 20 is endless. Starting the description of its course with the pulley 16, the chain passes off of the front edge of this pulley by the reach 30 over the lifting sheave 31, thence via the reach 32 to the rear edge of the pulley 15; from the front edge of this pulley a reach chain 33 extends around the idle pulley 34, from whence the reach 35 leads to the rear edge of the pulley 16. The lifting pulley is connected in a suitable manner with the load, for example, by the chain 40 shown as leading from the hook 41 of the pulley 31 over one or more idlers 42 to the load 43. The idle pulley 34 is suitably supported, and I find a convenient way to do this is to connect it by a cable 45 with the hook 41, this cable extending over the idler 46.

With the construction described, if the main shaft 13 is rotated by suitable mechanism, the chain extending around the lifting pulley 31 is pulled downwardly to raise the load or fed upwardly to lower the load, and such descent or rising of the load pulley 31 gives a complementary movement to the idle pulley 34 to take up the slack in the chain. For direct driving, the pulley 16 is held stationary by shifting it so that it clutches with the stationary teeth 27. This locks the chain reach 30 and then, if the rotation of the main shaft is in a direction to pull down on the reach 32, the load is raised rapidly. If the direction of rotation of the shaft is opposite, the load is lowered rapidly. If, on the other hand,

the pulley 16 is clutched with the pulley 15, the differential action slackens on the reach 30 whenever the reach 32 is pulled, and, accordingly, the load pulley 31 is given a very slow movement in one direction or the other for the same rotation of the main shaft which gives a rapid movement with the direct action. The actual direction which the rotation of the shaft gives to the lifting pulley 31 under these circumstances depends on which sprocket 15 or 16 has the larger number of teeth. As shown in the drawings, the sprocket 15 has the larger number of teeth, so that a right hand rotation of the main shaft pulls on the reach 32 farther than it slackens on the reach 30, thus raising the load. Accordingly, as shown, the right hand rotation raises the load whether the mechanism is differential or direct, or, if desired, one of these movements could be the reverse of the other by simply carrying the larger number of sprocket teeth on the other sprocket.

Any convenient means may be employed for shifting the movable sprocket and holding it in either extreme position. I have found it very satisfactory to employ a shiftable bar 50 slidably guided on the base 10 and having a pair of rollers 51 and 52 lying on opposite sides of the disk 24; and for shifting this bar I provide an eccentric 54 lying between the lugs 55 of the bar. The eccentric is mounted on a shaft 56 journaled in the frame and connected rigidly with an operating rock lever 57. This lever preferably extends normally in approximately horizontal position in which its own weight may hold it, wherefore, to change the operation from differential to direct, and vice versa, it is only necessary to throw the lever over to the opposite position.

Any suitable mechanism may be employed for rotating the shaft 13. I have shown a satisfactory device for this purpose adapted to be driven by an electric motor and give the desired slow rotation to the shaft 13. That mechanism will now be described.

60, in Fig. 1, indicates an electric motor, the armature shaft of which carries a pinion 62. This pinion meshes with a spur gear 63 on a shaft 64, but constantly clutched therewith by means of a clutch member 61 rigid with the shaft. This shaft is aligned with the shaft 13 and shown as supported in frame standards 65 and 66. The latter standard is preferably of disk-like form and coacts with the frame member 12 to form a suitable casing about some of the mechanism.

Keyed on the shaft 64 is a pinion 70 which meshes with a pair of spur gears 71 on opposite sides thereof. These gears are rigid on shafts 72 which are journaled in the frame standard 66 and in a box-like cas-

ing 69 secured thereto. Beyond the plate 66 each of these shafts 72 carries two eccentrics 74 and 75. These two pairs of eccentrics are mounted in two yokes 76 and 77 which have internal gear teeth 78 meshing with the teeth of a spur gear 79 rigid on the shaft 13. The result of the above construction is that, as the motor drives the shaft 64, this, through the gear and the eccentrics, gyrates the two yokes (one balancing the other), which gives a very slow rotation to the spur gear and thus to the shaft 13 to drive the hoisting pulleys.

Keyed on the shaft 64 is a bushing 80 on the squared portion of which are mounted friction disks 81 pressed toward a disk 82 which is loose on the bushing. This disk 82 has a cylindrical flange carrying rigid teeth 83 with which coacts a pawl 84. When the shaft is turned in the direction to raise the load, the friction disks and the disk 82 are rigid with the shaft in the direction allowed by the pawl 84, the pawl clicking idly over the teeth. When the rotation stops, however, the pawl prevents backward rotation of the disk 82, and this allows backward rotation of the shaft only by the slipping of the friction disks. The friction disks are pressed together on this backward rotation by means of the teeth of the clutch member 61 camming the wheel 63 toward the brake.

As shown, the brake comprises a series of disks 81 alternately loose on the bushing and connected with it, the loose disks having projecting portions 85 extending into suitable pockets in the flange of the disk 82, and such is the form illustrated, though it is to be understood that any number of disks may be used, as necessary. The friction which this mechanism provides may be sufficient to make the hoisting device self-locking, if desired, and is particularly valuable when the mechanism is directly driven with the sprocket wheel 16 held stationary.

The above described gyroscopic driving mechanism and friction brake are claimed in my prior Patents Nos. 757,333 and 946,253, to which reference is made for fuller description. In the present mechanism, when the sprocket wheel 16 is locked to its neighbor, the differential pulley itself makes a self-locking hoist, so that a brake mechanism is unnecessary. Accordingly, I provide for throwing out the pawl 84 when the two sprocket wheels are clutched together. This is accomplished simply by extending the slide 50 and providing it with a cam shoulder 87 which coacts with the tail 88 of the pawl to shift it to idle position when the slide is moved in that direction.

Having thus described my invention, what I claim is:

1. The combination of two sprocket wheels

having respectively different numbers of teeth, a chain formed in a loop and wrapping around both sprocket wheels, means for locking one of the wheels to the other or to an independent device, a brake adapted to retard the rotation of the other wheel, and means for automatically rendering the brake inactive when the sprocket wheels are locked to each other and active when one of them is locked to the independent device.

2. In a hoisting mechanism, the combination of two adjacent sprocket wheels having respectively different numbers of teeth, a chain formed in a loop and wrapping around both sprocket wheels, means for clutching one of the sprocket wheels to its neighbor or to a stationary device, as desired, a brake adapted to retard the rotation of the other wheel, and means for concurrently applying the brake and causing said clutching to the stationary device.

3. The combination of a shaft, a pair of adjacent sprocket wheels thereon, one tight on the shaft and one loose on the shaft, a stationary device on that side of the loose sprocket, which is opposite to the tight sprocket, means for shifting the loose sprocket alternatively into engagement with the tight sprocket or the stationary device, a brake adapted to retard the rotation of the shaft and means for automatically relieving the brake when the loose sprocket is locked to the tight sprocket.

4. In a hoisting mechanism, the combination of a shaft, a pair of sprocket wheels thereon having respectively different numbers of teeth, one of said sprocket wheels being fast on the shaft and the other loose, a chain formed in a loop and wrapping around both sprocket wheels, means for shifting one of said sprocket wheels to clutch it with its neighbor or with a stationary device, a brake on said shaft adapted to act in one direction of rotation thereof, and mechanism for throwing said brake out of action concurrently with the shifting of the movable pulley.

5. The combination of a shaft, a pair of

sprocket wheels having respectively different numbers of teeth, one rigid on the shaft and the other loose on the shaft and shiftable, means for clutching the shiftable wheel with its neighbor in one position and with a stationary device in the other position, an eccentric shaft, means engaging said shaft for shifting said pulley, a brake on said first mentioned shaft adapted to act when rotated in one direction, and mechanism for throwing said brake out of action by the means for shifting the movable pulley.

6. The combination of two independent sprocket wheels having respectively different numbers of teeth, means for driving one of said wheels, a chain looping around both sprocket wheels, a brake comprising a ratchet wheel frictionally connected with the driving device to rotate with it and a pawl adapted to engage the ratchet wheel and prevent backward rotation of it, means for relieving the friction of the brake to allow backward turning of the driven wheel independently of the ratchet, and shiftable mechanism adapted to connect the loose sprocket wheel with the driving device and withdraw the pawl from coaction with the ratchet wheel.

7. In a hoisting mechanism, the combination of two independent sprocket wheels having different numbers of teeth, a stationary device, means for clutching one of said sprocket wheels alternatively to the other sprocket wheel or to said stationary device, a chain wrapping around both sprocket wheels having two upwardly extending loops, a load pulley in one of said loops, a loose pulley in the other loop, and a flexible connection extending over a sheave and having each end attached to one of said pulleys.

In testimony whereof, I hereunto affix my signature in the presence of two witnesses.

EDWARD YOUNG MOORE.
